RACK FOR BEAMS

Morse A. Richtmyer, Blountville, Tenn., assignor
to Eastman Kodak Company, Rochester, N. Y.,
a corporation of New Jersey

Application April 9, 1948, Serial No. 20,078

9 Claims. (Cl. 211—13)

1

This invention relates to an apparatus and method for handling large spools containing yarn or similar filamentary or web material. More particularly this invention concerns apparatus and method for loading and transporting as well as storing large spools of yarn made from cellulose esters, especially such type of yarn put up on section beams or similar beams.

As is known in the industry, considerable yarn is put up on large spools or similar units of varying sizes and weights. Some of these beams of yarn may weigh only a few hundred pounds and be from 13" to 21" in diameter, whereas other of the beams or spools of yarn may be considerably larger in diameter, weighing, for example, a ton or more per beam.

The beams aforementioned upon which the yarn is wound, while a commercially available item, may vary in size of flange, shaft, and other component parts. This slight variation in size may be due to the fact that in some instances the empty section beams are constructed of wood carrying a steel shaft or some of the beams may be largely of metal construction from aluminum or magnesium alloys with a hollow end or similar recess.

It is apparent and as has been experienced in industry the handling of these heavy spools, aforementioned, presents a considerable problem not only because of the weight and tendency of the spools to roll during transportation, but also because it is highly important that the yarn or other filamentary material contained thereon not be damaged by the pressure of one beam upon another beam or otherwise.

One common type of handling of the aforementioned spools involves their transportation from the place of manufacture of the yarn to the textile mill wherein the yarn on the section beam is used. While the transportation may be accomplished by any common type of carrier, it is quite usual to transport the beams by motor truck.

Prior to my invention one way of handling these beams in truck-trailers has been to permanently build into the trailer or other carrier some type of large heavy and strong rack for supporting the weight. Such construction comprised, in general, a track so arranged as to receive and guide a plurality of beams as above described in rows on the outside edges of the beam flanges, thereby preventing lateral movement of the beams. The track holding the first row of beams is held fast to the floor of the truck trailer or railroad car. By means of another similar track positioned above the first row and secured to the truck a second row of beams may be accommodated. Rolling of the beams during transport is prevented by various methods and means such as clamps, chains, and

2

the like which, of course, add further weight to the truck load. In other words, the carrier has been equipped with a single large, strong longitudinally extending frame and the individual beams are stacked in this large frame.

Such prior constructions usually weigh between 1½ to 3 tons and unless completely utilized in each truckload, since they are substantially permanently affixed to the truck, add excessive tare weight to a shipment. The substantially permanent affixation of such a large frame structure renders the truck-trailer of limited use for other purposes. While such permanent construction permits of some flexibility in loading different size beams, this flexibility is rather limited. Also in the instance of shipping a partial load, as already mentioned, since the frame is more or less fixed, a large nonutilizable weight is being transported. Another disadvantage with respect to devices attached to the truck or other carrier is that even though the beams are adequately protected and handled during transportation in their delivery to the mill, unless the truck-trailer is left, the beams must be transferred to further protection or other steps taken for their protection. Similar remarks apply to the beams prior to their shipment.

After considerable study and experimentation I have found that a much improved apparatus and method may be employed for loading, transporting, or otherwise handling the spools of the type described. I have found that in general it is better to employ a plurality of small individual racks and to stack the racks, all of which will be described hereinafter in detail rather than to stack the beams in a single frame as has been a practice heretofore.

This invention has for one object to provide an improved apparatus and method for handling spools or beams of the class described. Another object is to provide a device suitable for handling spools, as aforementioned, that is light in weight and relatively inexpensive to construct. A still further object is to provide a device as just indicated which, even though being relatively light in weight and construction, still offers all the necessary protection that is required in the loading, transporting, or other handling of the yarn or similar material, aforementioned. Still a further object is to provide apparatus and a method which is more flexible in use in that beams of varying flange diameter may be accommodated and that other variables such as truck size and the like may be overcome in that the device of the present invention may be easily loaded and transported in all the usual common carriers without special construction affixed to that carrier. Various other objects, such as being able to operate with either a partial or full load, will be apparent as the description proceeds.

For a more complete understanding of the present invention reference is made to the attached drawings forming a part of the present specification.

In the attached drawing,

Figure 1 is a perspective view showing the over-all construction of one specific embodiment of an individual rack in accordance with the present invention.

Figure 2 is a similar view but shows a rack of the present invention loaded with a large section beam.

Figure 3 is also a perspective view showing the stacking of loaded individual racks.

Figure 4 is a diagrammatic end elevation view illustrating how a plurality of the racks in accordance with my invention may be loaded in a truck-trailer or the like for filling the truck space.

Figure 5 is also a diagrammatic side elevation view showing another method of loading a truck trailer or the like.

Figure 6 is a perspective view of another species of construction of an individual rack which, for example, may be used for carrying two small beams.

Referring to Figure 1, my individual rack per beam construction is made up of a light weight but strong rectangular frame or pallet marked by the over-all designation 2. While light weight metal angle members, such as regular angle iron or steel, may be used in the construction of frame 2, rigidity and strength are obtained by the double framing of 3, 4, 5, and 6, for example, which double framing is held together by tie strips as at 7, 8, 9, and 10.

This rectangular base or frame member just described carries corner posts 12, 13, 14, and 15 at the four corners thereof. It will be noted that these corner posts extend a substantial distance beyond the rectangular frame and may be suitably braced to the rectangular frame by means of brace members 17, 18, 19, and 20.

It will further be noted that the four corner posts extend a substantial distance below the rectangular frame member for forming legs 22, 23, and 24, for example. These legs serve to support the article to be carried a reasonable distance above the floor. In addition, as will be more apparent, during the consideration of Figure 3 the leg members and associated parts are so constructed that the individual rack of the present invention may be easily stacked above another rack. That is, it will be observed that each of the legs 22 and 23 are connected to the frame member by a piece of strip metal such as shown at 26, 27 and 28.

Referring specifically to part 27, it will be observed that a portion of this metal strip is formed at 31, before attachment to corner post 23, in a manner to provide a flat foot at 31 and also to provide a right angle shoulder 32 (see corner post 24) which aids in the aforementioned stacking.

Referring further to the rectangular frame member which has been given the over-all designation 2, at each end thereof there is provided the 45° pads best shown at 34, but also positioned toward the other corners 35, 36, and 37. By means of the angular positioning of these pads, as may be better understood from Figure 2 or Figure 4, the section beams are suitably supported at the flanges irrespective of the size of the flange, thereby eliminating any possibility of rolling motion of the beams during handling

or transit, but does not restrict endwise movement at this point. Endwise movement is taken by the plates to be described. These pads 34, 35, etc., may be covered with, for example, $\frac{1}{8}$ " thick belting, rubber or other similar material (not shown) in order to protect the flanges from becoming marred by direct contact with metal.

Referring now to the parts above the rectangular frame member 2, end abutment plates 38 and 39 are provided at each end of the rack. Suitable holes 40, one at each end, are lifting holes for crane hooks. These abutment plates include bracing member 41, 42, of plate 38 and 43 and 44 of plate 39. It will be observed that further bracing is attained from members 46, 47, 48, and 49. In addition, it will be observed that these last four mentioned members also function to provide a track surface, as, for example, at 51 and 52 for guiding the shaft of a beam into position in a channel, for example, at 53.

As pointed out, pad members such as 34 and 35 function to prevent rolling movement of the large spool of yarn contained in the rack and end plate members 38 and 39, with associate parts, function to prevent endwise movement. That is, this endwise movement of beam is taken at beam shaft ends, whereas in prior constructions endwise movement is taken at beam flanges which may cause damage to beam flanges and yarn. If desired pin holes, as shown at 54, may be provided so that the end of a section beam shaft can be pinned in place by conventional means in order to prevent upward movement. Usually, however, the weight of the section beam holds it in place.

Referring further to Figure 1, it will be observed that the track-brace members 46, 47, 48, and 49 are so attached to their respective corner posts as to provide an angular recess such as shown at 60 adapted to receive the feet 31 of another rack when stacking the racks.

Referring now to Figure 2, a rack such as shown in Figure 1 has been loaded with a large section beam. The loading may be accomplished by lowering the section beam 61 into the rack from the top, the members 51 and 52 providing a convenient track for guiding the ends of the section beam shaft into the channel 53 as already mentioned. The contents of the section beam are protected from below because of the adequate spacing, 62, of the beam above the floor. It will be noted from a consideration of further figures that in stacking there is adequate protective spacing between the beams from above.

Referring now to Figure 3, two loaded racks as shown stacked. As discussed above, the design and construction of my new rack is such that the shoulder members, as at 32, securely telescope and fit with the angular recesses as provided at 60 so that the racks may be easily stacked without danger of coming apart. Also pin holes may be provided at topmost ends of 12-13-14-15 so the conventional locking could be used when stacked, if desired. As may be further noted from Figure 3, adequate spacing 64 is had between the contents of the section beams so there is little danger of any portion of one section beam hitting against the contents of another section beam. The stacking of the racks, as shown in Figure 3, may be accomplished by a chain hoist which can be attached to the rack at numerous places such as at holes 40 provided at each abutment plate for superimposing one rack on a lower rack. Since my rack frame sets up off of the floor because of legs 22, 23,

and 24, there is ample working distance 66 so that the usual lift truck found around industrial plants may be rolled under the rack and the rack lifted for stacking or moving into the truck or box car or otherwise handled.

Referring to Figure 4, there is diagrammatically shown in this figure how a plurality of stacked racks may be loaded into a truck trailer. In Figure 4, the racks are loaded in a manner so that the axes of the section beams are parallel to the longitudinally dimension of the truck and truck motion.

Referring to Figure 5, it is also possible to load the truck trailer or box car so that the axes of the section beams are at right angles to the longitudinal dimension of the truck or other carrier. As already pointed out above, each section beam is individually held in the rack and my racks, whether positioned singularly or stacked, exhibit very little tendency to roll or otherwise move out of position when in transit. Hence, as noted from Figures 4 and 5, my individual racks per beam may be loaded and transported in any manner most convenient with respect to the particular space available in the truck or box car.

Referring now to Figure 6, there is shown another species of construction in accordance with the present invention. While the above description has been directed to an individual rack, namely, for a single beam, it is also possible to construct a rack in accordance with the present invention for holding two beams, commonly called warp beams in the trade. Usually when handling a beam weighing in excess of $\frac{1}{2}$ ton one beam per rack is ample. However, when handling smaller beams it is quite feasible to place two beams in a rack of the type shown in Figure 6, thereby obtaining a rack construction approaching a cube, which because of its equal dimensions, has considerable stability against rolling or upsetting.

In considering in further detail this alternative species of Figure 6 it will be observed that the main frame construction 72, the corner posts 73, 74, 75, and 76 are of a construction similar to that already set forth with respect to the preceding figures. Likewise, the feet construction at 77, 78, etc., is the same. Therefore, further description of similar parts is unnecessary and attention is directed to certain of the items characterizing the instant species.

In the species of Fig. 6, the beam is supported by its flanges on the angular track members 79 and 81 on the frame 72. These smaller beams are usually provided with a circular recess or aperture in each flange, and for this reason the members 82, 83, 84 and 85 are provided for engaging said recess or aperture and for holding the beams in position on the members 79 and 81. Each of the members 82, 83, 84 and 85 are secured to a plate 80 which is adapted to be swung outwardly about the hinged point 86 before loading the beams on the members 79 and 81. When the beams have been positioned in the rack, the plates 80 and their respective members 82, 83, 84 and 85 are swung toward the beams for engaging the recess or aperture in the flanges thereof. The plates 80 are held in position by the cross bars 87 and 88 which are pivotally mounted at 89 to one of said plates on each side and provided with a slot for engaging a stud on the other plates and which are then secured or locked in position by the wing nuts 90. The cross bars 87 and 88 are swung in an upward direction to permit the

plates 80 to be swung outwardly before the loading or unloading of the beams. The particular details of hinging and locking may be conventional and do not constitute a limitation on the present invention.

It will be observed that this alternative construction of Figure 6 is provided with an angular recess or channel, as indicated at 91, so that these racks which hold two beams may likewise be stacked one upon the other and stacked in trailer-trucks or other carriers, as discussed in connection with Figure 3, 4, and 5.

It is believed apparent from the preceding description that I have provided a simple and efficient construction for the convenient handling of large spools of yarn or the like which not only protects and supports the spool during transit but protects the spool prior to loading and after unloading.

As shown in Figures 4 and 5, the racks may be stacked in a truck or other conveyance for either a full or partial load, without the supporting members becoming an integral part of the conveyance. In the instance of a full truck, the weight of the supporting members comprising my individual racks, per beam, in the aggregate is substantially less than the weight of the supporting members formerly used as a part of the trailer. As already discussed, my construction lends itself to the handling of different size beams wherein the dimension of the beam flanges or beam shafts may vary somewhat. My individual racks per beam do not require any special equipment for loading or moving, but the usual lift trucks and the like found around textile plants function satisfactorily in picking up the rack, either endwise, or from the side. My construction also gives maximum protection to the beam as well as the yarn.

I claim:

1. An apparatus for handling, transporting, and storing large spools of materials, comprising a rectangular horizontal frame, vertically extending corner posts affixed to the corners of said frame, said corner posts extending below said frame member for forming legs, means cooperating with said legs and said frame for forming frame supporting feet, end plates secured to and extending vertically above said frame and substantially parallel to and between adjacent corner posts, said plates being securely braced with and from said frame and from the upper ends of said corner posts, the upper bracing also providing a track means toward said plates, and members associated with said plates adjoining said bracing which functions as a track means.

2. An apparatus for handling large spools of yarn, comprising a rectangular horizontal frame member, vertically extending corner posts affixed to the corners of said frame, said corner posts extending below said frame member for forming legs, means cooperating with said legs for forming frame supporting feet, end abutment plates secured to said frame and having braces extending above said frame, members associated with said abutment plates, and the corner posts extending above said bracing for providing recesses at the four corners of said apparatus.

3. An apparatus for handling, transporting, and storing large spools of yarn and the like filamentary materials, comprising a rectangular horizontal frame member made up of parallel elongated horizontal members tied together at a plurality of points by a plurality of strips, ver-

tically extending corner posts affixed to the corners of said parallel frame, said corner posts extending below said frame for forming legs, means cooperating with said legs and said frame for forming frame supporting feet, abutment end plates extending vertically above said frame between adjacent pairs of said corner posts, said end plates being braced with and from said frame and from said corner posts, members associated with said abutment plate and adjoining said bracing, the corner posts extending above said bracing in order to provide angular recesses at at least some of the corners of said apparatus adapted to receive the feet of apparatus of the class described in the stacking thereof.

4. An apparatus of the class described comprising a horizontal frame, vertically extending corner posts affixed to said frame and braced thereto, said corner posts extending below said frame member for forming legs, means cooperating with said legs and said frame for forming feet, end plates extending vertically above said frame, members associated with said plates and the corner posts extending slightly above said plates in order to provide angular recesses at the corners of said apparatus adapted to receive the feet of similar apparatus in the stacking thereof.

5. An apparatus for handling, transporting, and storing large spools of yarn, filamentary or web materials, comprising a horizontal rectangular frame made up of parallel angle iron units tied together at a plurality of points by a plurality of metal strips, vertically extending corner posts affixed to said frame and braced thereto, said posts extending below said frame member for forming legs, strips of metal cooperating with said legs and said frame for imparting rigidity and forming feet adapted to fit another apparatus of the class described in the stacking thereof, end abutment plates extending vertically above said frame and substantially parallel to said posts, said end plates being securely braced with and from said frame and said posts, the upper bracing also providing a track toward said abutment plate, members associated with said abutment plates and adjoining said bracing which functions as a track member, the posts extending slightly above said track bracing in order to provide angular recesses at at least some of the corners of said apparatus adapted to receive the feet of similar apparatus in the stacking thereof.

6. An apparatus for handling large spools comprising a horizontal rectangular frame member made up of parallel units tied together at a plurality of points, vertically extending corner posts affixed to the corners of said frame and braced thereto, said corner posts extending below said frame member for forming legs, strips of metal cooperating with said legs and said frame, end plates extending vertically above said frame being securely braced with and from said frame and corner posts, members associated with said plates, the corner posts extending slightly above said plates in order to provide angular recesses at the four corners of said apparatus.

7. An apparatus for handling, transporting, and storing large spools of yarn, filamentary or web materials, comprising a horizontal rectangular frame made up of parallel angle metal units tied together at a plurality of points by a plurality of strips, vertically extending corner posts affixed to the corners of said frame and braced thereto, said corner posts extending below said frame for forming legs, strips cooperating with said legs and said frame for imparting rigidity and forming feet, end abutment plates extending

10 vertically above said frame and substantially parallel to said corner posts, said end plates being securely braced with upper and lower bracing with and from said frame and said corner posts, the upper bracing also providing a track toward said abutment plate, members associated with said abutment plates and the corner posts extending slightly above said upper bracing in order to provide angular recesses at the four corners of said apparatus.

15 8. An apparatus for handling, transporting, and storing large spools of yarn, filamentary or web materials, comprising a horizontal rectangular frame made up of parallel angle metal units tied together at a plurality of points by a plurality of strips, said frame carrying a plurality of angular pads for receiving and supporting the flanges of said large spools, vertically extending corner posts affixed to the corners of said frame and braced thereto, said corner posts extending below said frame for forming legs, strips cooperating with said legs and said frame for imparting rigidity and forming feet, end abutment plates extending above said frame and substantially parallel to said corner posts, said end plates being securely braced with upper and lower bracing with and from said frame and said corner posts, the upper bracing also providing a track toward said abutment plate, members associated with said abutment plates and the corner posts extending slightly above said upper bracing in order to provide angular recesses at the four corners of said apparatus.

20 9. An apparatus combination for handling, transporting, and storing a plurality of large spools of yarn, comprising horizontal rectangular frames, vertically extending corner posts affixed to the corners of each of said frames and braced thereto, said corner posts extending below said frame member for forming legs, means cooperating with said legs and said frame for forming feet, said feet fitting into the recesses of another apparatus of the class described and stacked thereon, vertically extending end plates supported by said frame for holding said spools, said end plates being securely braced with and from said frame and from said corner posts by means of lower and upper bracings, respectively, the upper bracing also providing a track toward said plate for guiding the spool thereto, the corner posts extending slightly above said track bracing in order to provide said recesses for receiving the feet of another apparatus of the class described in the stacking thereof.
